APPARATUS FOR EXPANDING METAL TUBES

Adolf Steinecke, Komotau, Czechoslovakia

Application January 11, 1930, Serial No. 420,216,
and in Germany January 18, 1929

12 Claims. (Cl. 80—13)

The invention relates to a process and apparatus for expanding metal tubes over their entire length by means of oblique rolls.

Hitherto, tubes, especially those having a relatively large diameter and thin walls, have been produced on oblique roller mills, the rolls of which, are provided with working surfaces directed towards one another at a relatively pronounced angle in the plane extending through the axis of the rolls and the axis of a tube undergoing treatment by the rolls. A correspondingly tapered mandrel disposed within the tube and between the said rolls is arranged to counteract the whole of the working pressure of the rolls including the side thrust thereof. It is necessary that the mandrel does not change its predetermined position between the rolls as any displacement thereof relative to the rolls considerably affects the working of the rolls and the dimensions of the work produced. The first requirement for a reliable rolling operation is therefore the provision of means whereby the mandrel is maintained in a predetermined position with respect to the working surfaces of the rolls during the whole working process, so that uniformity of the work produced by the rolls is ensured. As the mandrel is disposed within a tube undergoing treatment the internal diameter of the tube necessarily imposes limitations upon the means employed for securing the mandrel in its working position. Heretofore the mandrel has always been secured to a rod which, depending upon the length of the tubes to be rolled and the degree of pressure of the rolls, is subject to varying degrees of alteration in length. The heating of a relatively long mandrel rod during the rolling process causes changes in the length of the rod, even when the rod is water-cooled, which consequently causes a displacement of the mandrel between the rolls. In order to overcome this difficulty, fine adjustments for the mandrel are used which permit, by careful observation of the rolling process, corrections in the position of the mandrel. The said corrections may be made during the rolling operation.

This process necessitates, however, a somewhat complicated apparatus and great attention therefore has to be paid to the rolling operations.

The present invention comprises a process for expanding metal tubes by means of obliquely disposed rolls characterized by the tubes being expanded and shaped to an oval configuration in cross-section between parallel working surfaces of rolls acting in conjunction with a relatively slightly conical mandrel disposed with the larg-

er end thereof in a direction corresponding to the direction of feed of the tube or between working surfaces of rolls relatively slightly inclined towards one another in a direction corresponding to the direction of feed of the tube acting in conjunction with a cylindrical mandrel.

Further the present invention comprises a process according to the preceding paragraph characterized by the tube after leaving the working surfaces of the rolls and mandrel, being shaped to a circular cross-section by guide means disposed exteriorly or interiorly of the tube.

Again according to the present invention there is provided a rolling mill for carrying out the process in accordance with either of the two preceding paragraphs characterized by the provision of a hollow conical guide having a circular or oval shaped mouth for the tubes for the purpose of shaping the oval tubes produced by the rolls to a circular cross-section and wherein the said guide is constituted by a portion of the rolls or by a separate unit connected to the mill.

The method set out above necessitates an alteration in the diameter of the rolls and a corresponding alteration in shape of the mandrel, and the disadvantageous alteration in the position of the mandrel with respect to the rolls hitherto experienced, due either to variations produced to the length of the mandrel rod or the insecurity of locating the same under the relatively very heavy roller pressure or by the heat generated during the rolling operation, does not affect the working of the rolls, and the operation of the mill is thereby simplified and cheapened. Further the faulty work hitherto caused by want of careful observation in the usual method of working described above, is eliminated.

It has already been proposed with calibrating roller mills, to use obliquely disposed rolls provided with parallel working surfaces. This arrangement, however, has only been used in order to bring small irregularities in the walls of tubes, for example at places where the wall is thicker than is desired, to the correct size and a stretching of the wall at such places is thereby caused with consequential local increases in the diameter of the tube.

In order to move the tube longitudinally over the mandrel by means of the said oblique rolls, a relatively lighter pressure must be exerted upon the wall of the tube between the rolls and the mandrel even on such places where it is correctly dimensioned. The local increases in the diameter of the tube produced as above described

- constitute undesirable additional work and the tubes must therefore subsequently be passed through a dimensioning rolling mill in order to obtain the desired uniform diameter of the tubes.
- 5 Further it has been proposed in the finishing process of rolling tubes, to roll the same alternately circular and oval in cross-section upon a mandrel, when both the section of the mandrel and that of the diameter of the rolls are arranged 10 to correspond with the alterations of the tubes from circular to oval, or in a further arrangement from an oval section to a similar oval section displaced therefrom about the axis of the tube by an angle of 90°.
- 15 The present invention, on the contrary, provides a continuous stretching of the substance of the walls of the tube over the whole length thereof, and an expansion of the tube between a mandrel and rolls co-acting therewith.
- 20 The invention is illustrated in the accompanying drawings of which Figure 1 illustrates diagrammatically details of a rolling mill constructed in accordance with the present invention.
- Figure 2 is a similar view to Figure 1, but illustrating a modification of this invention.
- Figure 3 illustrates a cross-section of the tube shown in Figure 1 with a mandrel disposed in the interior thereof.
- Figure 4 illustrates in longitudinal section a 30 guide for restoring the tubes of oval cross-section which leave rolls to a circular cross-section.
- Figure 5 illustrates in end elevation a modified form of guide.
- Figure 6 illustrates in longitudinal section the 35 guide illustrated in Figure 5 in conjunction with the rolls and mandrel of a rolling mill constructed in accordance with this invention and with a tube in the working position therein.
- Figure 7 is a view similar to Figure 6 of a 40 modified form of guide.
- Figure 8 is a view similar to Figure 6 of a modified form of guide.
- Figure 9 is a view similar to Figures 6 and 8 of a further modified form of guide.
- 45 Figure 10 is a view similar to Figure 1 but illustrating an internal form of guide for restoring the tubes to a circular cross-section.
- Figure 11 is a longitudinal sectional view at right angles to Figure 10.
- 50 Figure 12 is a transverse section of Figure 11.
- Figure 13 is a view similar to Figure 5 but showing another form of guide.
- Figure 14 is a longitudinal section similar to Figure 4.
- 55 Figure 15 is a view similar to Figure 13 but showing a further modified form of guide.
- Referring to Figure 1 of the drawings, the working surfaces *a* of the rolls *b* are disposed parallel to one another so that the space between 60 the rolls remains constant. The mandrel *c* is made slightly conical and the larger end is disposed in a direction corresponding to the direction of feed of the tubes.
- 65 Preferably, the larger end of the mandrel is of a diameter which ensures the required reduction in thickness of the walls of the tube. The working length of the mandrel is dependent, on the one hand, upon the circumference of the expanded tube and, on the other hand, on the circumferential speed of the rolls, that is to say, the stretching of the circumference of the tube must increase as the tube passes the rolls at about the same rate as the rate of increase in circumferential speed of the working faces of the rolls in order that the tube may not be twisted.

Instead of the disc rolls, illustrated in the drawings, so-called barrel rolls may if necessary be used. As shown by Figure 2 the working surfaces of the rolls may be disposed at a slight inclination to the axis of the mandrel in which case the 80 mandrel is purely cylindrical.

Preferably the smaller distance between the rolls, which is between the working surfaces of the edges thereof where the tube leaves the rolls, is chosen corresponding to the required reduction in thickness of the walls of the tube. As the space between the working surfaces of the rolls remains the same or is reduced an increase of the diameter of the tube in this direction is not possible, consequently, the tube *d* as shown in Figure 3 assumes a marked oval form in cross-section as shown at *d*¹ and retains this shape until it passes outside the range of the working surfaces of the rolls.

90 A tube leaving the expansion rolls is, as already stated, markedly oval and requires to be formed into a cylindrical shape. For this purpose, a tube may, for example, after leaving the expansion rolls be passed through a conical guide, the larger internal diameter of which corresponds to the larger external diameter of the oval tube, and the smaller diameter of which to the external diameter of the tube when restored to a cylindrical shape. The construction of the conical guide may be of various forms. The 105 guide may comprise a closed movable or stationary funnel. The first construction, Figure 4, is preferred to avoid sliding friction.

95 The walls of the conical guide may also be formed by roller *g* as shown by Figures 5 and 6. 110 These rollers may all run idly on their axes or be driven by spindles provided thereon, or again some may be driven and the remainder run idly on their axes.

As shown in Figure 7 one roller *g*¹ is driven 115 to force the tube, after leaving the rolls through the conical guide. The rollers are arranged to be adjustable and interchangeable according to the diameter of the tube to be rolled. It is to be understood that any number of rollers may be 120 arranged around the circumference of the conical guide, as required and in the examples shown in Figures 5 and 6, four rollers are used, equally spaced around the circumference. The axes of the rollers may be inclined relatively to the axis 125 of the tube as shown in Figures 8 and 9 for the purpose of imparting a longitudinal feeding movement to the tube and a mandrel *f* may be disposed within the tube. The same effect may be obtained by providing the rolls *b* with special 130 working surfaces *m*, Figures 10 to 12, which are arranged to act upon the tube as it passes over the cylindrical portion *l* of the mandrel *l*.

Instead of the above described movable external guide for forming the cylindrical tube, 135 internal guide means or a shaping device in the form of a mandrel *f* Figures 6 to 9, or of a mandrel *l*, connected to the roll mandrel *c*, Figures 10 and 11, may be used.

140 Instead of the movable guides a stationary shaping device, a closed stationary funnel *e*, Figures 13 and 14 may be used the wall of which may be discontinuous as shown in Figure 15, so that only relatively few guide pieces *e*¹ are used.

I claim:

145 1. An apparatus for expanding metal tubes comprising obliquely disposed rolls, the working surfaces of which are parallel, a relatively slightly conical mandrel disposed with the larger end thereof in a direction corresponding to the direc- 150

- tion of feed of the tubes and guide means exterior of the tubes for shaping the tubes to a circular cross-section.
2. An apparatus for expanding metal tubes comprising obliquely disposed rolls, the working surfaces of which are parallel, a relatively slightly conical mandrel disposed with the larger end thereof in a direction corresponding to the direction of feed of the tubes and guide means within the tubes for shaping the tubes to a circular cross-section. 80
3. An apparatus for expanding metal tubes comprising obliquely disposed rolls the working surfaces of which being relatively inclined towards one another in a direction corresponding to the direction of feed of the tube, a cylindrical mandrel and guide means exterior of the tubes for shaping the tubes to a circular cross-section. 85
4. An apparatus for expanding metal tubes comprising obliquely disposed rolls the working surfaces of which being relatively inclined towards one another in a direction corresponding to the direction of feed of the tube, a cylindrical mandrel and guide means within the tubes for shaping the tubes to circular cross-section. 90
5. An apparatus for expanding metal tubes comprising obliquely disposed rolls, a mandrel between the rolls and slightly inclined working surfaces towards the major axis of the tubes on one of them and a stationary guide for rounding the tube. 95
6. An apparatus for expanding metal tubes comprising obliquely disposed rolls, a mandrel between the rolls and slightly inclined working surfaces towards the major axis of the tubes on one of them and a hollow conical guide formed of straight edged members. 100
7. An apparatus for expanding metal tubes comprising obliquely disposed rolls, a mandrel between the rolls and slightly inclined working surfaces towards the major axis of the tubes on one of them, a hollow conical guide having a circular shaped mouth and a partly conical and partly cylindrical mandrel disposed co-axially within the conical guide. 105
8. An apparatus for expanding metal tubes comprising obliquely disposed rolls, a mandrel between the rolls and slightly inclined working surfaces towards the major axis of the tubes on one of them, a hollow conical guide having an oval shaped mouth and a partly conical and partly cylindrical mandrel disposed co-axially within the conical guide. 110
9. A tube expanding mill, comprising a pair of skew rolls provided with conical working faces formed to engage the outer surface of the wall of a tube parallel to its axis, and a mandrel between the rolls provided with a conical working face tapering outwardly in the direction of movement of a tube through the mill and positioned to cooperate with said roll faces to reduce the wall thickness and enlarge the diameter of the tube, the pass formed by said rolls and mandrel being of constant draft regardless of normal variations in the longitudinal position of the mandrel with relation to the rolls. 115
10. A tube expanding mill comprising obliquely disposed rolls having surfaces constituting a working face formed to engage the outer surface of the wall of a tube, and a mandrel between the rolls provided with a working face positioned to cooperate with said roll face to reduce the wall thickness and enlarge the diameter of the tube, one of said working faces being slightly inclined to the axis of the tube, the other of said working faces being substantially parallel to the axis of the tube, whereby the pass formed by said rolls and mandrel is of constant draft regardless of variations in the longitudinal position of the mandrel. 120
11. A tube expanding mill comprising obliquely disposed rolls and a mandrel, said rolls and mandrel having working surfaces one on said rolls and the other on said mandrel cooperating to reduce the wall thickness and enlarge the diameter of the tube by giving it an oval cross section, one of said working surfaces being inclined to the axis of the tube, the other being parallel to the axis of the tube, whereby the pass formed by said rolls and mandrel is of constant draft regardless of variations in the longitudinal position of the mandrel, and rounding means receiving the oval tube from the rolls and mandrel. 125
12. An apparatus for expanding metal tubes comprising obliquely disposed rolls as a unit, a mandrel between the rolls as another unit and a working surface on one of said units slightly inclined toward the major axis of the tube and working surfaces on the other of them parallel to said axis, said surfaces cooperating for thinning and expanding the tube into oval cross section of constant draft regardless of variations in the longitudinal position of the mandrel, and conical rounding surfaces receiving the oval tube leaving the rolls. 130
